UNITED STATES PATENT OFFICE.

FRANK E. LICHTENTHAELER, OF NEWTON, MASSACHUSETTS.

METHOD OF EXTRACTING ROSIN FROM RESINOUS WOOD.

1,104,912

Specification of Letters Patent. Patented July 28, 1914.

Application filed March 17, 1913. Serial No. 754,692.

To all whom it may concern:

Be it known that I, FRANK E. LICHTENTHAELER, a citizen of the United States, residing at Newton, in the county of Middlesex and State of Massachusetts, have invented certain new and useful Improvements in Methods of Extracting Rosin from Resinous Wood; and I do hereby declare the following to be a full, clear, and exact 10 description of the invention, such as will enable others skilled in the art to which it appertains to make and use the same.

The present invention relates to a method of extracting resins from resinous woods, 15 and more particularly to a method of removing rosin from resinous pine wood.

The object of the present invention is to produce a method of removing the resins from resinous woods in an undecomposed 20 condition, which is capable of being carried on with comparatively simple and economically operated apparatus and by means of which a good product can be produced upon a commercial basis and at a reasonable 25 manufacturing cost.

The present invention, in its broader aspects, contemplates the extraction of resin from all kinds of resinous wood by subjecting the wood to heat and steam in a vacuum.

30 The present invention, in its more limited aspects, contemplates more particularly the extraction of rosin or colophony from resinous pine wood.

Referring to resinous pine wood, and particularly to the wood of the live long-leaf pine tree of the Southern States of the United States, the wood contains a mixture of turpentine and resin. The dead wood of this species, commonly known as "bight 35 wood," also contains pine oil as well as turpentine and resin. The turpentine (an essential oil or terpene) and the resin (a resin), together with the pine oil (mostly terpineol) when present, are all soluble in 40 each other and exist in the wood as a mixture which is the oleo-resin of the pine wood. The oleo-resin, as it exists in its natural state in the wood or as it exudes from the wood, contains the turpentine and resin, 45 together with pine oil, when present, which are made up of definite chemical compounds. They are, however, capable of being easily decomposed into other chemical compounds by heat. The commercial value of turpentine, pine oil and resin is much greater 50 when they are in their natural and undecom-

posed condition than in a decomposed condition, so that from a commercial standpoint it is particularly desirable to extract them from the wood without decomposition. 60 That is to say, they should be extracted from the wood unchanged chemically from the condition in which they exist in the wood. The turpentine and pine oil are sufficiently volatile so that it has been possible to remove 65 them from the wood by various processes without subjecting the wood to sufficient heat to decompose them. The rosin, however, has resisted extraction by the methods generally employed for removing the turpentine and pine oil and has, therefore, generally been extracted separately by some solvent method, or left in the wood and subjected to destructive distillation. The rosin upon destructive distillation breaks down 70 into resin oils which are commercially less valuable than the rosin. It has also been proposed to obtain rosin from the pitchy "light wood" by heating the wood until the excess rosin oozes from the wood in a melted 75 condition and drips into the bottom of the container. The yield of rosin obtained by this method is, however, comparatively small.

I have discovered that if the resinous pine 80 wood be put into an air-tight receptacle and there subjected to steam at a temperature within certain limits in a vacuum of less than a certain absolute pressure, the rosin, in a chemically undecomposed condition, 85 will leave the wood in a vaporous mixture with the steam. This vaporous mixture of rosin and steam can afterward be condensed to separate the rosin and the water of condensation. The rosin is non-volatile under 90 ordinary conditions. The rosin can, however, be vaporized under certain conditions, and by vaporization as here used is meant a change of state from a solid or liquid into a vapor without undergoing chemical decomposition. Destructive distillation is not contemplated within the meaning of vaporization as employed in the following discussion. If the wood is subjected to steam at a 95 temperature above a certain critical minimum in a vacuum of less than a certain critical maximum absolute pressure, the rosin can be caused to leave the wood in a vaporous mixture with the steam. If the receptacle is merely exhausted and heated, it is 100 impossible to cause the rosin to leave the wood as a vapor no matter how low the ab- 105

solute pressure within the receptacle or how high the temperature. However, if steam is present, it assists the transformation of the rosin from a liquid to a vapor state, so that if certain critical conditions of pressure and temperature are realized, the rosin can be compelled to leave the wood in a vaporized condition. Even in the presence of steam, the rosin will not pass from a liquid to a vapor state no matter how high the temperature, unless the pressure of the surrounding space is less than a certain critical maximum. That is to say, there is a certain critical pressure below which the surrounding space must be maintained if the rosin is to be vaporized in the presence of steam. This critical pressure may be designated as the critical maximum pressure of vaporization of rosin in the presence of steam. Moreover, even in the presence of steam, the rosin will not pass from a liquid to a vapor state no matter how low the pressure, unless the temperature is greater than a certain critical minimum. That is to say, there is a certain critical temperature above which it is necessary to heat the rosin if the rosin is to be vaporized in the presence of steam. This critical temperature may be designated as the critical minimum temperature of vaporization of rosin in the presence of steam. If the resinous pine wood is put into an air-tight receptacle which is exhausted to a vacuum of absolute pressure less than the critical maximum pressure of vaporization of rosin in the presence of steam and there subjected to steam at a temperature higher than the critical minimum temperature of vaporization of rosin in the presence of steam, the rosin can be made to leave the wood in a vaporous mixture with the steam, and this vaporous mixture of rosin and steam can be condensed and the rosin obtained in the same chemical condition in which it existed in the wood.

In the drawing, the preferred form of apparatus used in extracting rosin from resinous wood in accordance with the method of the present invention is diagrammatically illustrated in elevation.

Referring to the drawing, a charge of resinous wood is put into a closed, air-tight receptacle or retort 2 which is provided with an air-tight door 4. The wood 6 in billet form is loaded onto a car 8 and run into the receptacle 2. While it is preferred to use the wood in billet form because it is in better sizes for charcoal upon subsequent destructive distillation, nevertheless, the present invention is not limited to the treatment of wood in billet form, because, under some circumstances, it may be advantageous to comminute or chip the wood before it is put into the receptacle. A steam pipe 10, having a valve 11, is provided for discharging steam through distributing nozzles 12 into the receptacle. A water-cooled condenser 14 is connected by means of a pipe 16 to the receptacle. The condenser 14 consists of a number of vertical condenser tubes 18 extending between two heads or diaphragms 20. Water is admitted through a water connection 22, provided with a valve 24, into the intertubular space of the condenser 14 to maintain it at the required temperature so that the distillate from the wood is condensed as it flows downward through the condenser tubes 18. The condensate is collected in two receivers 26 and 28 which are connected through valves 30 and 32 respectively with the drain pipe 34 coming from the condenser 14. The receivers 26 and 28 are provided with discharge or drip valves 36 and 38 by means of which the collected condensate may be drawn off. The receivers 26 and 28 are connected through valves 40 and 42 respectively with the exhaust pipe 44 leading to a vacuum pump 46 which maintains a vacuum in the entire apparatus. Air cocks 48 and 58, located just below the valves 40 and 42, are provided for letting air into the receivers 26 and 28 respectively.

The method as carried on with the illustrated apparatus and with particular reference to the extraction of rosin from the resinous dead pine wood, is as follows:—The charge of wood 6 is run into the receptacle 2 and the door 4 is clamped in place. The valve 24 is opened to admit water to the condenser 14 and the valves 30, 32, 40 and 42 are opened to connect the apparatus to the vacuum pump 46, which exhausts the air from the entire apparatus. After the required vacuum is established, one of the receivers, say for example the receiver 28, is shut off from the rest of the apparatus by closing the valves 32 and 42. The valve 11 is then opened to admit superheated steam into the receptacle 2 through the nozzles 12. While it is preferred to superheat the steam to the required temperature, heat may be applied directly to the receptacle to assist in maintaining the required temperature in the receptacle or to increase the temperature of the steam. As the presence of steam is one of the essential conditions of the present method, steam must be present in the receptacle, but it might be introduced at a lower temperature, or possibly even as water, if the receptacle were independently heated. As soon as the wood is heated by the steam, the distillate leave the wood in a vaporous mixture with the steam. The vaporous mixture passes over into the condenser 14 where it is condensed and from which it runs into the receiver 26. The first portion of the distillate is practically all turpentine, because turpentine is more easily vaporized than the other constituents of the oleo-resin in the wood. As the extraction is continued, the distillate grows progres-

sively poorer in turpentine and richer in resin until the last portion of the distillate is practically all resin. The pine oil, which is present in the dead wood and is less volatile than turpentine and more volatile than resin, passes over with the turpentine and resin. The entire extracting operation requires from 8 to 94 hours, depending upon a number of conditions, such as the size of the wood, the temperature and pressure in the receptacle, the amount of steam used, etc. It is preferred to exhaust the receptacle to a pressure of about 2 pounds per square inch absolute pressure and to maintain this degree of exhaustion in the apparatus throughout the entire extracting operation. The vacuum is read by means of a vacuum gage such as is commonly used with the condensers of steam engines and which reads the difference of pressure between the vacuum and the atmosphere in inches of mercury. A vacuum of about 2 pounds absolute pressure will be read on the vacuum gage as 23 inches of mercury. It is preferred to superheat the steam so that after it has expanded in the expanded steam in the receptacle will have a temperature of about 950° Fahrenheit. It is to be understood that this statement of the preferred pressure and temperature is only approximate, because good results can be obtained even with variations from this pressure and temperature. The pressure in the receptacle can increase to about 33 pounds per square inch absolute pressure. The temperature can be allowed to fall to about 230° centigrade. The temperature must not be increased so that the distillate is decomposed by the heat.

The pressure and temperatures stated above are as accurate as I have been able to obtain them. It is to be understood, however, that these statements are only approximate and that in pointing out the invention in the claims, I do not wish to limit myself to the exact temperatures and pressures stated, but to include within the scope of the claims some variation from these pressures and temperatures. While the pressure may be allowed to rise to about the critical maximum pressure of vaporization of resin in the presence of steam, or the temperature may be allowed to fall to about the critical minimum temperature of vaporization in the presence of steam, nevertheless, in order to extract the resin as rapidly as possible, the pressure should be lower than the critical pressure and the temperature higher than the critical temperature.

The turpentine and pine oil, when present, as they are evaporated from the wood by my method, tend to carry the resin with them, and it is easier, therefore, to extract the oleo-resinous mixture of turpentine, pine oil and resin than it is to extract them sepa-

rately. Since the object of the present invention is primarily to extract the resin, it is within the purview of the present invention to extract resin from wood after the turpentine and pine oil have been removed. However, as it is easier to extract the resin along with the turpentine and pine oil, the preferred method of carrying out the invention is to extract the turpentine and pine oil as well as the resin in the same operation.

The mixture of turpentine, pine oil and resin which is extracted from the wood in a vaporized condition passes over as a vaporous mixture with the steam into the condenser 14 where the vaporous mixture is condensed into water and the crude mixture of turpentine, pine oil and resin which has been designated as oleo-resin and the first run of which is practically all of turpentine and the last run of which is practically all resin. The water and oleo-resin are discharged through the open valve 30 into the receiver 26. After the receiver 26 is full, the valves 33 and 42 are opened and the valves 30 and 40 are closed so that the condensate is then discharged and collected in the receiver 28. To empty the receiver 26, the air cock 48 is opened to admit air, and the condensate is drained off through the valve 36, after which the valves 36 and 48 are again closed so that the receiver 26 can be used when the receiver 28 is cut out and supplied in a similar manner. Since the first run of the condensate is rich in turpentine, the condenser 14 will have to be maintained at a fairly low temperature. As the extracting operation is continued, the condensate grows continuously richer in resin, so that the condenser 14 must not be maintained cold enough to congeal the resin and so clog up the condenser tubes 18. The temperature of the condenser 14 can be increased as the condensate grows richer in resin by cutting down the circulation of water. The condensate collected in the receivers 26 and 28 is separated from the water of the condenser by some flotation method and the collected crude oleo-resinous mixture may be afterward subjected to some form of fractional distillation to separate it into turpentine, pine oil and resin, although the vaporized oleo-resin coming from the receptacle 2 might be fractionally condensed. If the live pine wood is treated, there is no pine oil present. The wood, after its removal from the receptacle, is not only free from oils and resin, but the water has been practically all removed, so that it is in an ideal state for destructive distillation.

While I have described and claimed my method as a method of extracting resin, it will be evident that it may be employed to extract other resins, and consequently the term resin as used in the specification and claims is intended as a term of description.

rather than limitation and to include other resins having the characteristics of rosin.

While the preferred method has been illustrated and described, it is to be understood that the present invention is not limited to all the details set forth in the description, but may be embodied in other methods within the scope of the invention as defined in the following claims.

10 I claim--

1. The method of extracting rosin from resinous wood which consists in putting the wood in an air-tight receptacle, in exhausting the receptacle and in subjecting the wood to the action of heat and steam to cause the rosin to leave the wood in a vaporous mixture with the steam, and in condensing the vaporous mixture of rosin and steam.

20 2. The method of extracting rosin from resinous wood which consists in putting the wood in an air-tight receptacle, in exhausting the receptacle to about 2 pounds per square inch absolute pressure and subjecting the wood to steam at a temperature of about 250° centigrade to cause the rosin to leave the wood in a vaporous mixture with the steam, and in condensing the vaporous mixture of rosin and steam.

3. The method of extracting rosin from resinous wood which consists in putting the wood into an air-tight receptacle, in exhausting the receptacle to less than about 3½ pounds per square inch absolute pressure and subjecting the wood to steam at a temperature higher than about 230° centigrade to cause the rosin to leave the wood in a vaporous mixture with the steam, and in condensing the vaporous mixture of rosin and steam.

4. The method of extracting rosin from resinous wood which consists in putting the wood into an air-tight receptacle, in exhausting the receptacle to an absolute pressure less than the critical maximum pressure of vaporization of rosin in the presence of steam and subjecting the wood to steam at a temperature higher than the critical minimum temperature of vaporization of rosin in the presence of steam to cause the rosin to leave the wood in a vaporous mixture with the steam, and in condensing the vaporous mixture of rosin and steam.
